UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

ELECTRIC COUPLING DEVICE.

1,263,521.

Specification of Letters Patent. Patented Apr. 23, 1918.

Application filed May 12, 1914, Serial No. 837,990. Renewed September 7, 1916. Serial No. 118,947.

To all whom it may concern:

Be it known that I, THOMAS R. BROWN, a citizen of the United States, residing at Sparkill, in the county of Rockland and State of New York, have invented new and useful Improvements in Electric Coupling Devices, of which the following is a specification.

This invention relates to electric train line couplings, and more particularly to that type of coupling in which the coupling head is provided with a plurality of fixed contacts connected to the respective train line circuits and a movable contact carrier adapted to be automatically projected into a counterpart coupling for electrically connecting the fixed contacts and thereby the electric train line circuits.

One object of my invention is to provide an electric train line coupling of the above type in which the contact carrier is moved by the action of a tappet controlled system of levers upon engagement of contact carriers in counterpart coupling heads.

Another object of my invention is to provide an improved fluid pressure controlled device for releasing the couplings and returning the parts to normal position.

In the accompanying drawing, Figure 1 is a sectional plan view of counterpart coupling heads embodying my invention and shown in the coupled position; Fig. 2 is a similar view of a coupling head with the parts in normal position; Fig. 3 a detail sectional view on the line *a—a* of Fig. 2; and Fig. 4 a detail sectional view on the line *b—b* of Fig. 2.

According to my present invention, the coupling head may comprise a suitable casing 1, containing a horizontally movable contact carrier or slide 2 which may be provided with a plurality of contacts adapted upon projection of the slide to electrically connect corresponding fixed contacts in the coupling heads and thereby the respective train line circuits.

For the sake of simplicity, the above mentioned contacts are not shown in the drawings, but may be similar to the arrangement shown in my pending application, Serial No. 828466, filed March 31, 1914, as will be evident.

At one side of the contact carrier 2 a tap-

pet 3 is mounted in the casing 1, so as to normally project out beyond the meeting face 4 of the coupling head, and to the stem 5 of said tappet is pivotally connected a link 6 of a toggle lever connection. The other link 7 is pivotally connected to the link 6 and includes a coil spring 8. The link 7 is pivotally connected to a lever 9 fulcrumed at 10 to the casing 1 and said lever has its long arm pivotally connected to a rod 11 which in turn is pivoted on the contact carrier 2.

A roller 12 is mounted on the pivot pin 13 connecting the toggle links 6 and 7 and a cam projection 14 is provided on the contact carrier in position to engage the roller 12 upon inward movement of the carrier from normal position.

As shown in Fig. 2 of the drawing, in the normal position of the parts, the contact carrier 2 projects out from the meeting face 4 of the coupling to a slight extent and the links 6 and 7 are in line, with the tappet 3 projecting from the meeting face 4. In coupling, as counterpart coupling heads approach, the tappet 3 of one coupling first engages the meeting face of the other coupling and the spring 8 of the toggle link 7 in each coupling head is thereupon compressed.

The meeting faces of the contact carriers 2 then engage and since the resistance of the springs 8 and the friction of the parts can never be exactly the same in two couplings, it will be evident that one of the contact carriers 2 will give way against the superior resisting power of the other and consequently cause a retractive movement of this contact carrier which will cause the cam projection 14 to engage the roller 12 of the toggle lever connection. The roller 12 is thus moved outwardly so that the links 6 and 7 are thrown out of alinement and this permits the spring 8 to relax, so as to exert no pressure through the lever connections on the contact carrier 2. On the other coupling, however, the toggle links 8 remain in alinement and consequently, continued movement of the tappet 3 acts through the lever 9 and the rod 11 to shift or project the corresponding contact carrier into the counterpart coupling. Since the resistance of the other contact carrier to movement is

removed as previously explained, the same will be shifted rearwardly by the action of the projected contact carrier. In this position, the contacts on the projected carrier 5 electrically connect the fixed contacts in the counterpart couplings and thereby the electric train line circuits.

In order to release the couplings, a tripping finger 15 is provided on the link 7 in 10 position to be engaged by a tappet 16 which may be operated pneumatically or manually.

For operating the tappet pneumatically, the tappet 16 is provided with a piston 17, subject on one side to a spring 18 tending 15 to hold the tappet in its retracted position and having a pipe 19 opening to the opposite side.

A passage 20 leads from this side of the piston 17 to the tappet 3 and registers with 20 a passage 21 through the tappet. The passage 21 opens into chamber 22 at the rear of the tappet 3 and since the passage 20 also communicates with said chamber, it will be clear that when fluid under pressure is admitted to the piston 17 on one car, the same will also flow to the piston 17 of the coupling on the other car.

In uncoupling, when fluid is supplied to the piston 17 on one car, said piston and the 30 corresponding piston on the other car will be shifted so as to cause the tappet 16 to act on the finger 15 of the coupling, having its contact carrier projected. The toggle lever mechanism is thereupon tripped and the 35 links 6 and 7 are thrown out of alignment.

The expansion of the spring 8 then acts to draw the projected carrier back to release position so that the couplings may be uncoupled.

40 Upon separation of the coupling heads, the tappet 3 on each coupling is forced outwardly to normal position by a spring 23, causing the links 6 and 7 to assume their normal positions, as shown in Fig. 2 of the 45 drawing.

A push rod 24 may be attached to the tappet 16 so as to permit of operating the trip finger 15 manually when desired.

Having now described my invention, what 50 I claim as new and desire to secure by Letters Patent is:—

1. In an electric train line coupling, the combination with a movable contact carrier adapted to be projected into a counterpart 55 coupler for electrically connecting the train line circuits, of a mechanism including a spring operatively connected with the contact carrier, a tappet for compressing said spring, and means operated by the yielding 60 movement of one of the carriers to actuate said mechanism to project the other contact carrier upon the coming together of the counterpart couplers.

2. In an electric train line coupling, the 65 combination with a movable contact carrier

adapted to be projected into a counterpart coupling for electrically connecting the train line circuits, of a toggle lever mechanism including a spring and operatively connected with the contact carrier, a tappet 70 for compressing said spring, and means operated by the yielding of one of the carriers for actuating said lever mechanism to project the other contact carrier upon the coming together of counterpart couplings. 75

3. In an electric train line coupling, the combination with a movable contact carrier adapted to be projected into a counterpart coupling for electrically connecting the train line circuits, of a toggle lever mechanism including a spring and operatively connected to the contact carrier, a tappet 80 for compressing the spring, and means operated upon engagement of the counterpart contact carriers for tripping one of the toggle lever mechanisms.

4. In an electric train line coupling, the combination with a movable contact carrier adapted to be projected into a counterpart coupling for electrically connecting the train line circuits, of a mechanical trip mechanism, including a spring acting on 90 said carrier, a tappet operated by engagement with a counterpart coupling for compressing said spring, and means associated 95 with the contact carrier for tripping the mechanical trip mechanism upon engagement of counterpart contact carriers.

5. In an electric train line coupling, the combination with a movable contact carrier 100 adapted to be projected into a counterpart coupling for electrically connecting the train line circuits, of a mechanical trip mechanism, including a spring acting on said carrier, a tappet operated by engagement with a counterpart coupling for compressing said spring, and a projection carried by the contact carrier for tripping the mechanical trip mechanism upon engagement 105 of counterpart contact carriers. 110

6. In an electric train line coupling, the combination with a movable contact carrier adapted to be projected into a counterpart coupler for electrically connecting the train line circuits, of a toggle lever mechanism 115 including a spring operatively connected with the contact carrier, a tappet for compressing said spring, means operated by the yielding movement of a contact carrier for shifting said toggle mechanism, and a 120 spring for resetting the toggle mechanism upon separation of the couplers.

7. In an electric train line coupling, the combination with a movable contact carrier adapted to be projected into a counterpart 125 coupling for electrically connecting the train line circuits, of a toggle lever mechanism containing a spring and operative to project the contact carrier, a tappet for operating said toggle lever mechanism and for 130

compressing said spring upon engagement of counterpart couplings, a projection on the contact carrier for automatically tripping the toggle lever mechanism, and manually controlled means for tripping the toggle lever mechanism when the contact carrier is in the projected position.

In testimony whereof I have hereunto set my hand.

THOMAS R. BROWN.
